[57] CLAIM

The ornamental design for a knife with guard means, substantially as shown and described.

DESCRIPTION

FIG. 1 is a rear perspective view from below and one side of the knife with the guard means in a first position; FIG. 2 is a rear perspective view of the knife illustrated in FIG. 1 from below and other side with guard means in alternative position;

FIG. 3 is an elevation of the other side of the knife illustrated in FIG. 1;

FIG. 4 is a plan view of the knife illustrated in FIGS. 1 and 2; and

FIG. 5 is a front view of the knife illustrated in FIG. 1.
